PORTABLE RADIO RECEIVER

George M. Buckler, Fayetteville, N.Y., assignor to
General Electric Company

Filed Jan. 11, 1972, Ser. No. 217,078

Term of patent 14 years

Int. Cl. D14—03

U.S. Cl. D56—4 B

FIG. 1

FIG. 2

FIG. 3

FIG. 4

FIG. 1 is a top perspective view of a portable radio receiver showing my new design;

FIG. 2 is a top plan view;

FIG. 3 is a side elevational view; and

FIG. 4 is a bottom perspective view thereof.

Portions of the radio are shown in the drawing of FIGS. 1 through 4 have been provided with diagonal lines for indicating surface transparency, and portions have been stippled for indicating contrasting surface appearance.

I claim:

The ornamental design for a portable radio receiver, substantially as shown and described.
